UNITED STATES PATENT OFFICE.

CHARLES CAMPBELL, DUNCAN CAMPBELL, AND MERLE N. McGILL, OF PHILADELPHIA,
PENNSYLVANIA.

DESIGN FOR A CASTER-STAND.

53,566.

Specification for Design.

Patented July 15, 1919.

Application filed April 18, 1919. Serial No. 291,138. Term of patent 14 years.

To all whom it may concern:

Be it known that we, CHARLES CAMPBELL and DUNCAN CAMPBELL, subjects of the King of Great Britain, and MERLE N. McGILL, a citizen of the United States, residing at Philadelphia, in the county of Philadelphia and State of Pennsylvania, have invented a new, original, and ornamental Caster-Stand, of which the following is a specification, reference being had to the

accompanying drawing, forming a part thereof.

The figure is a side elevation of the caster stand, illustrating our new design.

We claim;

The ornamental design for a caster stand, as shown.

CHARLES CAMPBELL.
DUNCAN CAMPBELL.
MERLE N. McGILL.
